UNITED STATES PATENT OFFICE.

JACOB M. FLEGLE, OF WEBSTER GROVES, MISSOURI.

POCKET-CLOSER.

1,086,039.

Specification of Letters Patent.

Patented Feb. 3, 1914.

Application filed January 23, 1912. Serial No. 672,988.

To all whom it may concern:

Be it known that I, JACOB M. FLEGLE, a citizen of the United States, residing at Webster Groves, county of St. Louis, Missouri, have invented a new and useful Pocket-Closer, of which the following is a specification.

This invention relates to improvements in pocket closers, and has for an object to provide a convenient and effective device for holding the open or free end of pockets yieldingly closed, thereby preventing articles placed within the pockets from being lost therefrom, and yet permitting the ready access to the pocket by the wearer of the garment of which the pockets are a part.

Another object of the invention is to prevent the ready tampering with the contents of a pocket constructed in accordance with my invention, the arrangement being such that it would be very difficult for an exterior agency to extract articles from pockets including my improvement without detection by the wearer of the garment of which the pockets are a part.

To these and other ends I have produced the novel arrangement and combination of elements hereinafter illustrated, described and claimed.

In the accompanying drawings, forming a part of this specification, and in which like characters of reference indicate like parts throughout the several views; Figure 1 is a detached perspective view of my improvement in complete form ready for application to a pocket formed in any character of garment; Fig. 2 is a transverse sectional view on the line 2—2 of Fig. 1; Fig. 3 is a vertical transverse sectional view showing the fabric of the pocket with the closing device in position; Fig. 4 is a horizontal sectional view, substantially on the line 4—4 of Fig. 3; Fig. 5 is a fragmentary transverse vertical sectional view of the upper part of a pocket with the pocket closing device in place and illustrates the details of the preferred manner of placing the pocket closing device in inner pockets of a garment; Fig. 6 is a fragmentary view, illustrating the details of one end of the plate which constitutes one portion of my invention. Fig. 7 is a horizontal sectional view, substantially on the line 7—7 of Fig. 6, illustrating clearly the rounded bearing portion for the elastic element; and Fig. 8 is a vertical elevation of a portion of a garment

with a pocket formed therein, part of the fabric being broken away to illustrate clearly the manner of applying my improvement.

In the accompanying illustrations 1 indicates a strip formed preferably from some suitable flexible metal. The strip 1 is curved, as will be clearly apparent by reference to Figs. 1 and 4; so that when the device is placed in position near the upper portion of a pocket formed in a garment, the concave surface of the strip 1 will conform closely to the body of the wearer, permitting the device to be worn without discomfort and without altering the shape of the garment. The said strip 1 is slightly widened at each end to form a relatively wide downwardly extending ear 2, the purpose of which is to prevent the strip from turning when placed in position in the garment in the manner hereinafter explained. A notch or channel is formed in the strip 1 by stamping or cutting out a small portion of each end of the strip and turning the metal backwardly against the convex surface of the strip, thus forming a rounded seat 3 upon which the elastic element 4 rests; the ears or projections 5 which form the sides of the channel prevent vertical movement of the elastic element, thereby retaining it in proper relation to the strip 1. Perforations, or holes, 6 are formed in each end of the strip 1 near the upper and lower edges thereof; thus providing means, whereby the strip 1 may be affixed or sewed to one of the pocket walls. The elastic element 4 is preferably in the form of a band and may be made of any suitable material such, for instance, as india rubber, elastic tape or the like. The length of the elastic band 4 should be less than that of the strip so that when the band is placed in the channels formed by the projections 5 the band will be stretched or put under tension, thereby holding one strand of the elastic element yieldingly against the convex surface of the strip, the other strand of the band being clamped to the strip by suitable clamp elements 7 placed at suitable and convenient positions, effectively to prevent displacement of the said element 4.

The manner of applying the device to the pocket is clearly apparent by reference to Fig. 8. The strip 1 is placed between the lining 8 and the inner pocket wall 10 near the open end of the pocket, in such a manner that the concave inner surface of the strip will rest against the lining 8 of the

garment. The strip is then bound or affixed in position by passing strands of thread back and forth through the perforations 6 as clearly appears at 9, (Fig. 8). A band 5 or binding of fabric may be placed over the strip, or the strip may be merely incased in a hem formed in the fabric wall 10 of the pocket.

It will be apparent, as has been suggested, that the strip being of flexible material may be curved so as to conform to the body of the wearer of the garment, thus preventing any discomfort in its use or bulging or mis-shaping of the garment to which it has 15 been applied. The strand of the elastic element which is free and rests yieldingly against convex surface of the strip is incased in a hem 11 formed in the outer wall 12 of the pocket or may be bound against 20 the wall by a separate binding if desired. The outer strand of the elastic element being under tension, the tendency thereof would be to draw the wall of the pocket, to which it is affixed, toward the opposite wall 25 containing the strip. Apparently, therefore, the normal position of a pocket equipped with my improvement will be closed, preventing the articles contained within the pocket from accidentally slipping out and being lost therefrom. As the 30 elastic element 4 is yielding, access to the pocket may be readily gained by merely manually separating the walls of the pocket and placing the hand within, the pocket 35 closing immediately upon the hand being withdrawn, as will be readily understood.

In using the device in combination with pockets formed on the inner part of a garment, the position of the strip may be reversed, as shown in Fig. 5. In this view 40 it is apparent that the strip is inserted in

the free wall of the pocket and the elastic placed in the opposite wall. This arrangement prevents the device from being apparent from the exterior of the garment, 45 and has a tendency to cause the garment to fit neatly about the body of the wearer.

Having thus fully described my invention, what I claim and desire to secure by Letters Patent is—

In a pocket closer, the combination of a garment, a lining, an inner pocket wall and an outer pocket wall between said lining and said garment and having slits near each side thereof, a metal strip having its upper edge in the same transverse plane throughout between the inner pocket wall and the lining, a portion at each end of said strip doubled backwardly upon said strip effectively to form a rounded band seat, a projection above said band seat, an ear integral with said strip near each end thereof below said band seat and extending downwardly relatively a considerable distance, said projections and said ears having holes therein 65 above and below said band seats, stitches passing through said holes and through the inner pocket wall, an elastic band passing through said slits across the entire inner side of said strip and being seated in said band 70 seats, and clamp elements separate from said strip encircling said strip and the inner part of said band remote from the ends of said strip, substantially as specified.

In witness whereof, I have signed this 75 specification in the presence of two subscribing witnesses.

JACOB M. FLEGLE.
